Inventor
Peter L. Markey
By John P. Smith Atty

UNITED STATES PATENT OFFICE.

PETER L. MARKEY, OF CHICAGO, ILLINOIS.

CUFF FASTENER.

Application filed July 18, 1927. Serial No. 206,424.

This invention relates to a new and improved cuff fastener which is adapted to be detachably fastened adjacent the edges of the cuff for securing the cuff together.

5 One of the objects of the present invention is to provide a new and improved form of cuff fasteners which are adapted to be detachably connected to the edges of the cuff for more conveniently securing and symmetrically connecting the cuff portions with each other so as to hold the cuff in better form and increase the style of the same.

10 A further object of the invention is to provide an improved cuff fastening means which can be quickly attached to or detached from the edges of the cuff and which may be easily and conveniently manipulated so as to detach the cuff fastening means from each other by the thumb and one finger of 15 one hand.

These and other objects are accomplished by providing a construction and an arrangement of the various parts in a manner hereinafter described and particularly pointed 20 out in the appended claims.

Referring to the drawings,

Fig. 1 is a top plan view of a shirt sleeve cuff showing my improved fastening means mounted thereon.

25 Fig. 2 is an enlarged bottom plan view of the hook member of my improved cuff fastener.

Fig. 3 is an enlarged top plan view of the eye member of my cuff fastening device.

30 Fig. 4 is an enlarged bottom plan view of the eye member of my cuff fastening device.

Fig. 5 is an enlarged side elevational view of the eye fastening member shown in Figure 4.

35 Fig. 6 is an enlarged transverse cross-sectional view of the eye and hook fastening members showing them connected together in the manner in which they secure the edges of the cuff together, and

40 Fig. 7 is an enlarged front elevation view of the cuff fastener shown in Fig. 6.

In illustrating one embodiment of my invention I have shown the same as comprising a hook fastening member generally referred to by reference character 10 and an eye fastening member generally referred to by the reference character 11. These members are preferably made of sheet metal spring material, and are adapted to be

5 mounted on the opposite edges 12 of a cuff 13 formed on a sleeve 14. These cuff fastening members 10 and 11 are provided with inner adjacent flat portions 14 and 15 respectively and outer parallel flat portions 16 and 17, respectively connected together so as to 60 form substantially U shaped portions as clearly indicated in Fig. 6. Each of these outer flat portions 16 and 17 of the members 10 and 11 respectively, are provided with identical clamping and piercing mechanism 65 and it is therefore believed that the description of one will suffice for the description of the other. The flat portions 16 and 17 of the clamping members 10 and 11 respectively, have formed integrally therewith 70 oppositely positioned upstanding portions 18. These upstanding portions 18 are provided with aligned apertures 19 which has pivotally mounted therein, an operating lever 20. Formed integrally with each of the flat portions 75 16 and 17 and extending into the space between these flat portions and the opposite flat portions 14 and 15 respectively are a plurality of prongs or piercing members 21 which are adapted to pierce or penetrate the 80 entire edge of the cuffs for securing the separate members to the adjacent edges of the cuff. Extending rearwardly from the flat portions 16 and 17 of each of the members 10 and 11 are two oppositely rolled portions 22 85 which have their ends connected together by a transverse integral portion 23. The material cut from between the rolled portion 22 and the transverse bar 23 is folded around as shown at 24 so as to form a substantially 90 U shaped portion and has its free end thereof extending parallel to the flat portions 16 and 17 of the respective members 10 and 11. The lever 20 is provided with two outwardly 95 projecting lugs 25 which are mounted in the apertures 19 in the upstanding portions 18 for pivotally supporting the levers to each of these members. The lever 20 is provided with a downwardly or right-angularly bent camming portion 26 which is adapted 100 to engage a central portion 27 which carries the piercing or penetrating members 21. This central portion 27 is separated from the flat portion 17 by having the material cut out on both sides as indicated at 28. From the 105 above description it will be readily seen that as the lever 20 is thrown from the locked position as shown in Figs. 5 and 6, through

substantially an angular movement, of 180 degrees, the camming portion 26 of the lever will engage the under surface of the portion 24 of the member 11 and thereby with-
5 draw the piercing points 21 from the mate-
rial or cuff. By this construction, it will
be seen that the operating lever, in addition
to locking and forcing the penetrating points
21 into the cuff also performs a function of
10 removing the penetrating points from the
material of the cuff when it is swung to a
position as above described.

The essential difference between the mem-
bers 10 and 11 of my improved cuff fasten-
ing means consists essentially of one being
15 provided with two transverse slots 28' and
29 so as to form a transverse raised bar 30
which forms the eye for the hook member.
The other member 10 is provided with a
hook as shown at 31 which is adapted to be
20 inserted in the aperture 28' of the eye mem-
ber for locking the same on the eye 30 of the
member 11. Extending rearwardly on the
opposite sides of the hook 31 are two out-
25 wardly extending spring portions 32 which
extend at an angle and are adapted to en-
gage the under surface of the flat portion 15
of the eye member for locking the hook 31
on the eye 30 of the member 11. It will be
30 noted that the spring portions 32 extend an-
gularly away from the hook member 10 so
as to cause the eye member to swing so that
the position of the outer edges of each of
35 these members are held under contact by
spring tension so as to support the edges of
the cuff in their proper position when the
cuff fastener is in its operative position or in
a position as shown in Fig. 6. This permits
40 the cuff to assume a very convenient and
neat appearance and prevents the crowding
of the cuff or utilization of the space as is
usually occasioned by the cuff fastener of
other styles. This construction of the cuff
45 fastening means permits the easy and con-
venient disengagement of these fasteners
from each other with the simple manipula-
tion of a thumb and forefinger by merely
gripping the rolled portions 22 of each of
50 the members 10 and 11 with the thumb and
forefinger and pressing them together, there-
by compressing the springs 32 so that the
surfaces 14 and 15 of each of these members
are not substantially parallel, after which
55 the hook member 10 is slid forwardly with
respect to the eye member and the pressure
is then released causing the hook to dis-
engage from the eye. By a similar operation,
the members are readily hooked and engaged
60 with one another by similarly employing
the thumb and forefinger of one hand.

While in the above specification, I have
described one embodiment which my invention
65 may assume in practice, it will, of
course, be understood that the same is ca-
pable of modification and that modification

may be made without departing from the
spirit and scope of the invention as ex-
pressed in the following claims.

What I claim as my invention and desire
70 to secure by Letters Patent is:

1. A cuff fastener comprising a hook and
eye member adapted to be attached to the
opposite edges of a cuff, penetrating means
75 formed integrally with each of the said
members, a lever mounted on said members
for forcing said penetrating means through
the material of said cuff and for withdrawing
said members from the material of the cuff,
80 a hook formed on one of said members, an
eye formed on the other of said members, and
spring portions formed on one of said mem-
bers and engageable with the other of said
members for locking said members together.

2. A cuff fastener comprising two separate
85 members detachably fastened to the opposite
adjacent edges of a cuff, an eye formed on
one of said members, a hook formed on the
other of said members and spring means
90 formed integrally with one of said members
and engageable with the other of said mem-
bers for holding said hook and eye under
spring tension.

3. A cuff fastener comprising two members
95 adapted to be attached adjacent opposite
edges of a cuff, a hook formed on one of
said members, an eye formed on the other
of said members and means formed on one
of said members and engageable with the
100 other for spreading said members away from
each other in a direction to bring their
outer edges in contact with each other.

4. A cuff fastener comprising two separate
members made of sheet metal and bent sub-
stantially in U shaped form to engage the
opposite sides of both edges of a cuff, a lever
105 actuated piercing means carried by the out-
side portion of said members, a hook formed
on the under side near the center of one of
said members, an eye formed near the center
110 of the under side of the other member and
spring actuated means formed integrally
with one of said members and engaging the
other of said members for actuating said
members in a direction about the hook and
115 eye of each of said members.

5. A cuff fastener comprising hook and
eye members adapted to be detachably fas-
tened to the opposite adjacent edges of a
cuff, penetrating means formed integrally
120 with said members, a lever pivotally mount-
ed on said members and adapted for actuating
said penetrating members, an eye formed on
one of said members and a hook formed on
the other of said members and angularly ex-
125 tends spring portions formed integrally with
said hook member and adapted to engage said
eye member for locking said hook and eye member under spring
tension.

6. A cuff fastener consisting of a mem-
130

ber made of a single piece of sheet spring metal and bent so as to form a substantially U shaped cross-section for engaging the opposite sides of a cuff, one of the legs of said U shaped portion being cut out so as to form a free center portion therebetween, penetrating means carried adjacent the end of said center portion, a lever pivotally mounted on said member and adapted to engage said center portion and means formed on said center portion for permitting said lever to withdraw said penetrating means from the cuff.

7. A cuff fastener comprising two mem- bers adapted to be attached adjacent the opposite edges of the cuff, a hook formed on the under side near the center of one of said members, an eye formed near the center of the under side of the other of said members, and means formed on one of said members and engageable with the other of said members for spreading said members away from each other in a direction to bring their outer edges in contact with each other.

In testimony whereof I have signed my name to this specification, on this 16th day of July, A. D. 1927.

PETER L. MARKEY.
